(57) **CLAIM**

The ornamental design for a glove, as shown and described.

DESCRIPTION

FIG. 1 is a dorsal side perspective view of a glove; FIG. 2 is a front elevation view thereof; FIG. 3 is a rear elevation view thereof; FIG. 4 is a side elevation view thereof; FIG. 5 is another side elevation view thereof; and, FIG. 6 is a dorsal side top plan view thereof.

The broken lines shown in the figures represent portions of the glove that form no part of the claimed design. The palm side of the glove forms no part of the claimed design.
